UNITED STATES PATENT OFFICE.

FREDERICK A. RUHL, OF STOCKTON, CALIFORNIA.

LIFT-PUMP.

No. 848,857.

Specification of Letters Patent.

Patented April 2, 1907.

Application filed June 7, 1906. Serial No. 320,556.

To all whom it may concern:

Be it known that I, FREDERICK A. RUHL, a citizen of the United States, and a resident of Stockton, in the county of San Joaquin, State of California, have invented certain new and useful Improvements in Lift-Pumps; and I do declare the following to be a full, clear, and exact description of the same, such as will enable others skilled in the art to 5 to which it appertains to make and use the same, reference being had to the accompanying drawings, and the characters of reference marked thereon, which form a part of this specification.

15 This invention relates to pumps, and particularly to that class known as "lift-pumps," used for deep-well pumping and the like.

The object of the present invention is to produce a pump of improved construction 20 and designed more particularly for use in deep wells and capable of being readily removed for renewal and repairs.

The device is designed more particularly for that class of pumps having a tubular 25 plunger and external packing adapted to engage the interior of the well-tubing and with an internal valve and with a foot-valve adapted to bear upon a seat connected to the lower end of the well-tubing.

30 The present invention is designed to facilitate the removal of the plunger with its internal valve and likewise remove the foot-valve at the same time that the plunger is removed.

35 With these and other objects in view the invention consists in certain novel features of construction, as hereafter shown and described, and specifically pointed out in the claims.

40 In the drawings similar characters of reference indicate corresponding parts in the several views.

Figure 1 is a sectional view of my device as arranged in the well, showing the plunger 45 in its lowest position. Fig. 2 is a similar view showing the plunger in its highest position. Fig. 3 is a sectional view, enlarged, of the valve and plunger portions of the improved device detached.

50 1 designates the casing of the well, and 2 is seat for the foot-valve at the lower end of the casing.

3 is a spring-cage adapted to be placed just above the valve-seat 2 and is provided with 55 cross-pieces 4 and 5.

6 is the lower or foot valve bearing on the seat 2 and provided with a stem 7, extending through the cross-piece 4, said stem 7 being provided at its upper end with a transverse stop-pin 8 to limit the movement of the 60 valve.

9 designates the plunger-rod, to the lower end of which is secured a tube 10, around the lower end of which tube is disposed the plunger-packing 11.

13 is a rod secured in the cross-piece 5 at the lower end and provided at its upper end with a lateral head 14, said rod extending slidably through an orifice in a cage 12 depending from the lower end of the packing 70 member 11.

15 is the upper or plunger valve, seated on the top of the tube 10 and inclosed in a cage 16.

In using the device the cage 12 slips up and 75 down on the rod 13, said rod extending into the tube 10 on the downward stroke of the plunger.

When it is desired to repair the foot-valve, or any other part of the mechanism, the 80 plunger-rod 9 is given quick short jerks, to release the movable parts and enable them to be readily withdrawn, they all being connected by means of the rod 13, with its enlarged head 14 bearing on the cage 12, and 85 the stem 7, with its cross-pin 8, adapted to bear on the cross-piece 4.

The length of the stroke of the plunger may be regulated by means of the length of the tube 10 and rod 13.

90 In pumping oil brass balls may be substituted for the form of valves shown in the drawings.

Iron pipe, iron tubing, brass tubing, or galvanized-iron pipe can of course be used in 95 conducting the water or oil to the surface of the well. Thus it can be readily seen that I have produced a pump whereby all the movable parts may be easily removed from the well when it is desired to repair them.

100 Having thus described my invention, what I claim as new and useful, and desire to secure by Letters Patent, is—

1. In a pump, a plunger having an external packing and an internal valve and with a 105 depending guiding device, a foot-valve structure consisting of spaced transverse members and connecting vertical members spaced apart and extending above and below the transverse members, resilient members con- 110

- nected respectively to said spaced vertical members and extending outwardly therefrom, a valve having a stem slidably engaging one of said transverse members, and a 5 rod connected to the other of said transverse members and slidably engaging said guiding device and with a terminal lateral head for bearing upon said guiding device when the plunger is in its elevated position.
- 10 2. In a pump, a foot-valve structure consisting of transverse members and spaced apart and connected by a plurality of spaced vertical members extending above and below the transverse members, resilient members

connected respectively to said vertical members and extending laterally therefrom, a 15 valve having a stem slidably engaging one of said transverse members, and a rod connected to the other of said transverse members and adapted to slidably engage the plunger of the 20 pump.

In testimony whereof I affix my signature in presence of two witnesses.

FREDERICK A. RUHL.
